US0D1100745S

(12) **United States Design Patent** (10) **Patent No.:** **US D1,100,745 S**
(45) **Date of Patent:** **** Nov. 4, 2025**

(54) **VEHICLE**

(71) Applicant: **VOLVO CAR CORPORATION**, Gothenburg (SE)

(72) Inventor: **Alex Chan**, Gothenburg (SE)

(73) Assignee: **Volvo Car Corporation**, Gothenburg (SE)

(**) Term: **15 Years**

(21) Appl. No.: **29/935,398**

(22) Filed: **Apr. 1, 2024**

(30) **Foreign Application Priority Data**

Oct. 5, 2023 (EM) 015036089-0001

(51) LOC (15) Cl. **12-08**

(52) U.S. Cl.

USPC **D12/92**

(58) **Field of Classification Search**

USPC D12/82, 84, 86, 89, 90, 91, 92, 93, 94, D12/96, 97, 98, 99, 100, 190, 196

CPC B62D 25/00; B62D 25/06; B62D 25/08; B62D 31/00; B62D 31/003; B62D 31/02; B62D 33/00; B62D 47/00

See application file for complete search history.
